CLUTCHED HEAD WRENCH WITH SPRING
PRESSED WEDGING BALLJames R. Schmitt and Seth E. Hickerson,
Enonca City, Okla.

Application October 7, 1946; Serial No. 701,692

2 Claims. (Cl. 81—58)

1

This invention relates to new and useful improvements in a ratchet tool, and has particular reference to ratchet wrenches.

The principal purpose of the present invention is the provision of a ratchet wrench having a head carried by a body member, said head being adapted to rotate freely in one direction with respect to said body member, and adapted to be secured against rotation in the opposite direction by means of a ball retained in a recess provided by a groove of uniform depth formed in the periphery of said head and a groove of tapering depth formed in the wall of said body member adjacent said head.

Another object of the present invention is the provision of a positive means for positioning said locking ball in operative position to said body member and turning head, thereby adapting said ratchet wrench for use in any position.

Further objects are simplicity and ruggedness of construction, and adaptability for use as either a left hand or a right hand wrench.

With these objects in view, as well as other objects which will appear during the course of the specification, reference will be had to the drawing, wherein:

Figure 1 is a perspective view of a ratchet wrench embodying the present invention.

Fig. 2 is an enlarged fragmentary sectional view taken on a central plane through the body member of the wrench.

Fig. 3 is a section taken on line III—III of Figure 2.

Like reference numerals apply to similar parts throughout the several views, and the numeral 10 refers to a body member having one end shaped to form a handle 12 and the opposite end of which forms a substantially circular ring 14 the aperture 16 of said ring being of substantially cylindrical form. Said ring is divided at a point adjacent handle 12 by slit 18. The portions of ring 14 adjacent said slit are enlarged to form outwardly extending shoulders 20 and 22. A machine screw 24, which passes through shoulder 20 and slit 18 and is adjustably threaded into shoulder 22, serves to adjust the size of aperture 16 of ring 14 by closing said slit against the resilience of said ring.

Carried for rotation in aperture 16 of ring 14 is a flat cylindrical head 26 snugly fitting therein. A groove 28 of substantially semi-circular cross-section is formed to extend entirely around the periphery of said head. A relatively short groove 30 of arcuate cross-section is formed in the inside wall of ring 14 in operative alignment with groove 55 of head 26 and body member 10 is permitted.

28 formed in the periphery of head 26. Said groove extends from slit 18 and inclines toward the inner wall of ring 14. The recess formed by the cooperation of grooves 28 and 30 is therefore of tapering thickness. A hardened ball 32 is contained within said recess, the diameter of said ball being such that it fits loosely in said recess at the deep point of groove 30, but wedges tightly if moved toward the shallow end of said groove. Said ball is constantly urged toward the shallow end of said groove by means of spring 34 contained in hole 36 in ring 14. Said spring bears at its inner end against ball 32, and its outer end abuts against screw plug 38 threaded into hole 36. The tension of said spring may be varied by adjusting screw plug 38.

Centrally positioned in head 26 is an axial hole 40 of square cross-section, adapted to receive a tool bar, not shown, to which may be attached wrench sockets or other tools.

The wrench may be assembled by springing slit 18 open and inserting head 26 into aperture 16. At the same time ball 32, resting in groove 28 of said head, passes transversely through slit 18 into groove 30 in ring 14. A corner 42 of ring 14 adjacent said slit is cut back to facilitate the insertion of said ball. Screw 42 is then inserted and tightened until ring 14 is drawn into the proper fit about head 26, and spring 34 and screw plug 38 are inserted in hole 36, said screw plug being advanced to provide the desired tension in said spring. Ball 32 prevents the removal of head 26 from aperture 16, and said head is prevented from canting in said aperture by its close fit therein.

When the handle 12 is turned in the direction indicated by the arrow in Figure 2, ball 32 is forced toward the shallow end of groove 30, where it wedges tightly between ring 14 and head 26. Head 26 is thus secured to said ring, and rotates therewith. There is virtually no lost motion when beginning rotation in this direction, since ball 32 is at all times urged toward the wedging position by spring 34. Since said spring also prevents said ball from falling to the deepest end of groove 30 when said groove extends downwardly the wrench may be used in any position.

When handle 12 is rotated in a direction opposite to that indicated by the arrow in Figure 2, ball 32 is urged toward the deep end of groove 30 against the pressure of spring 34. Since said ball then lies at a point where the recess formed by grooves 28 and 30 is of greater depth than the diameter of said ball, free relative rotation of head 26 and body member 10 is permitted.

The graduation of the depth of groove 30 must be sufficiently steep to prevent jamming of the ball at a shallow point of said groove, with consequent difficulty in backing of handle 12 in a direction opposite to the arrow in Figure 2. At the same time, the slope of said groove must be sufficiently gradual to prevent slippage of said ball in groove 28 when advancing handle 12. It has been found practical to slope said groove approximately two one-hundredths of an inch per one-eighth inch travel.

The ratchet wrench may be adapted for use as either a left hand or right hand tool by extending the tool bar carried in hole 40 of head 26 from one face or the other of said head, and is thus a simplification over wrenches requiring the reversal of a pawl with respect to a toothed ratchet wheel, or other internal adjustment.

The improvements we claim as new and desire to protect by Letters Patent are:

1. A ratchet tool comprising a body member in the form of a split ring with the ends thereof spaced apart, a screw joining the ends of said ring whereby the size thereof may be adjusted; a head rotatably carried by said body member and adapted to carry a wrench socket or the like, and having a peripheral groove formed in the edge thereof, said groove cooperating with a relatively short groove of graduated depth formed in said body member; a spherical wedging ball carried in the recess formed by said grooves whereby relative rotation in one direction of said body member and said turning head is prevented and relative rotation of said last two named parts in the opposite direction is permitted; and a spring of adjustable tension carried by said body member whereby said wedging ball is constantly urged toward the wedging position.

2. A ratchet tool comprising a body member having a substantially cylindrical hole formed therethrough forming a ring, said ring being split and having formed in the inner wall thereof a relatively short groove of tapering depth extend-

ing in one direction from said split; a screw joining the ends of said split ring whereby the diameter thereof may be adjusted; a handle integral with said ring whereby said ring may be manually rotated; a substantially cylindrical head carried for rotation in said split ring, said head being adapted to carry a wrench socket or the like and having a peripheral groove of uniform depth formed in the edge thereof and cooperating with said tapered groove formed in said split ring; a wedging ball carried in the recess formed by said grooves whereby relative rotation of said split ring and said turning head is prevented in one direction and permitted in the opposite direction; and a spring carried in a recess formed therefor in said split ring at the opposite side of the split from said tapered groove, and bearing against said ball, whereby said wedging ball is constantly urged toward the shallow end of said tapered groove.
